(57) CLAIM

The ornamental design for a cup, as shown and described.

DESCRIPTION

FIG. 1 is a top plan view of a first embodiment of the cup, showing my new design, with the bottom plan view being a mirror image thereof;

FIG. 2 is a top perspective view thereof;

FIG. 3 is a side elevation view thereof, with the opposite side being identical thereto;

FIG. 4 is a side cross-sectional view of the cup of FIG. 3, taken in the direction of line 4—4;

FIG. 5 is a top plan view of a second embodiment of the cup, showing my new design, with the bottom plan view being a mirror image thereof;

FIG. 6 is a top perspective view thereof;

FIG. 7 is a side elevation view thereof, with the opposite side being identical thereto; and,

FIG. 8 is a side cross-sectional view of the cup of FIG. 3, taken in the direction of line 8—8.
